DESCRIPTION

FIG. 1 is a top front perspective view of the first embodiment of a vehicle daytime running lamp bezel, showing our new design;

FIG. 2 is a bottom front perspective view thereof;

FIG. 3 is a top rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The second embodiment of the vehicle daytime running lamp bezel is a mirror image of the first embodiment disclosed in FIGS. 1 through 9 and is not shown.
